UNITED STATES PATENT OFFICE.

EMORY C. ATHERTON, OF MINNEAPOLIS, MINNESOTA.

SHELL-LOADING MACHINE.

1,258,736.

Specification of Letters Patent. Patented Mar. 12, 1918.

Application filed August 12, 1916. Serial No. 114,588.

To all whom it may concern:

Be it known that I, EMORY C. ATHERTON, a citizen of the United States, residing at Minneapolis, in the county of Hennepin and 5 State of Minnesota, have invented certain new and useful Improvements in Shell-Loading Machines; and I do hereby declare the following to be a full, clear, and exact description of the invention, such as will enable others skilled in the art to which it 10 appertains to make and use the same.

This invention has for its object to provide an improved shell loading machine which may be conveniently operated by foot 15 and includes a novel type of shell holder which is automatically moved forwardly from under the rammer or plunger when the operating foot pedal is released whereby the shells may be conveniently loaded into 20 the holder and removed therefrom, as desired.

Another object is the provision of a shell loading machine embodying a novel type of yieldable rammer and recoil spring associated therewith.

With these and other objects in view the invention consists in the novel construction, combination and arrangement of parts as will be hereinafter specifically described, 30 claimed and illustrated in the accompanying drawings, in which—

Figure 1 represents a vertical longitudinal sectional view through the improved shell loader.

Fig. 2 represents a top plan view thereof.

Fig. 3 represents a transverse sectional view on the line 3—3 of Fig. 1.

Fig. 4 represents a fragmentary side elevation showing the primer ejecting attachment, partly in section.

Fig. 5 represents an enlarged fragmentary sectional view of the shell loader showing the primer inserting attachment in detail.

Fig. 6 represents a fragmentary front elevation of the loading machine illustrating a part of the primer inserting mechanism applied thereto.

Referring to the drawings in detail, where in similar reference numerals designate corresponding parts throughout the several views, the numeral 10 indicates a table or other suitable support upon which is secured a bed plate 11, having an undercut groove 12 in the top thereof slidably receiving the horizontally slidable bar 13 having connections at its rear end with an actuating

chain 14. The chain 14 is extended over a pulley 15 at the rear end of the bed plate 11 and is connected at its lower terminal with a foot pedal 16. A spring 17 is interposed in the chain 14. A stop screw 18 is adjustably fitted in a strap 19 fastened to the bed plate 11 and is adapted to be engaged by an angular arm 20 secured to the slide bar 13 for limiting the rearward sliding movement of the latter. The forward movement of the slide bar 13 is limited by a stop 21 which is secured in position by a screw 22 and is adapted to engage the foot of the standard 24 which latter is bolted as 60 indicated at 25 to the bed plate 11 and straddles the slide bar 13. The slide bar is normally retained in forwardly extended position by means of a spring 26 which is connected at one end with the vertical portion 70 of the stop arm 20 and is connected at its opposite end with the foot 23 of the vertical standard or upright.

The upper section 27 of a vertically movable slide bar is slidably mounted in a channel or groove 28 formed in the front face of the upright 24 and is connected by screws or equivalent means 29 with the lower section 30 which latter projects downwardly through openings 31 and 32 in the slide bar 80 13 and bed plate 11, respectively. The opening 31 in the slide bar 12 is elongated so as to permit longitudinal movement of the bar independently of the vertically disposed slide bar. The vertical slide bar is 85 normally retained in elevated position by the tension of a coil spring 33 and is adapted to be depressed by the foot lever or pedal 16, the movement of the pedal being transmitted to the slide bar by a chain or other 90 flexible connecting element 34. There is sufficient slack in the chain 34 to permit the slide bar 13 to be moved to its rearmost position before the movement of the pedal is 95 transmitted to the vertical slide bar through 100 the chain 34.

A cylinder 35 is bolted in the upper section of the vertical slide bar and the upper and lower ends thereof are closed by caps or heads 36. A plunger or rod 37 is fitted 105 through the lower cap or head 36 and is provided at its upper terminal with a flange or head 38 which is snugly fitted in the bore of the cylinder 35 and is adapted to reciprocate vertically therein. The lower terminal 110 of the plunger 37 is connected by a coupling 39 with a detachable rammer 40. A spring

41 is confined between the upper head 36 and the head 38 and normally retains the plunger in downwardly extended position. A recoil spring 42 is confined between the 5 lower head 36 and the plunger head 38 and is adapted to absorb the recoil movement of the plunger as will be hereinafter more fully explained.

A stop screw 43 is fitted in the upper cylinder head 36 and is adapted to engage the upper terminal of the plunger 37 to limit the upward movement of the latter within the cylinder. The lower cylinder head 36 is formed with an upstanding flange 44 constituting a stop for the head 38 of the plunger whereby when the latter is engaged with the screw 43 the plunger is rigidly held against movement in the cylinder between the flange 44 and the screw 43.

20 The forward extremity of the slide bar 13 is formed with an internally screw threaded aperture 45 in which is detachably secured the integral externally screw threaded stem 46 of the base member 47 of the shell holder which latter is designated generally by the numeral 48. The upper open end of the cylindrical base member 47 is formed with a bayonet slot 49 adapted to receive a laterally projecting pin 50 carried by the shell holder 51 whereby the latter is secured in operative position in the base member 47. A cap 52 is detachably secured to the upper open end of the holder 51 and secures a plurality of spring guard members 53 in position in the shell holder.

40 The primer extracting or removing attachment for the loading machine is illustrated in detail in Fig. 4 and it comprises a post 54 adapted to be secured in the opening 45 in the slide bar 13, subsequent to the removal of the base member 47 and carrying an upstanding pin 55. The shell is adapted to be positioned over the post 54, in an inverted position, and the pin 55 engages the primer of the shell. A cylindrical member 56 is secured to the coupling member 39 subsequent to the removal of the rammer 40 and is formed in its lower terminal with a recess 57 into which the primer is ejected during the down stroke of the plunger or rod 37.

45 The primer setting attachment for the shell loader comprises an attaching plate 58 having vertical slots 59 therein receiving screws 60 whereby the plate is adjustably secured in position upon the upright or standard 24. The attaching plate 58 carries a horizontally disposed plate 61 under which is secured a plate 62. The two plates 61 and 62 are formed with vertically aligned and 50 internally screw-threaded apertures 63 in which are fitted externally screw-threaded sleeves 64 having vertically aligned bores 65. A slot is formed between the two plates 61 and 62 and slidably receives a stop plate 66 having an aperture 67 therein adapted to

be moved in registration with the bores of the sleeves 64, which latter are arranged above and below the stop plate 66. The rear end of the plate 66 is connected with an angular shell engaging member 68 which is 70 normally retained in forwardly extended position by the tension of the spring 69 and it is adapted to be engaged by a shell 70 shown in dotted lines in Fig. 5, to effect rearward movement of the member 68 and 75 the plate 66 so as to move the aperture 67 of the latter into registration with the bores of the sleeves 64. The shell is supported in position upon a post 71 secured in position in the aperture 45 in the slide bar 13 and 80 having a recess 72 in the upper terminal thereof. A primer inserting plug 73 is detachably secured to the coupling member 39 subsequent to the removal of the rammer 40, and it is provided with a reduced extension 85 74 arranged in vertical line and adapted for insertion into the bores 65 in the sleeves 64.

In the operation of the improved shell loading machine, it is first necessary to eject or remove the original primer and this is accomplished by adjusting the screw 43 until the inner terminal thereof engages and moves the head or flange 38 of the plunger 37 against the flange 44 of the lower cylinder head 36, thus rigidly securing the plunger in 95 position in the cylinder. The cylindrical member 56 is subsequently inserted in the coupling member 39 and the post 54 is secured in position upon the slide bar 13 and the shell is placed, in inverted position, upon the post 54. The foot pedal 16 is subsequently depressed and the downward movement of the forward extremity thereof effects a rearward movement of the slide plate 13 through the chain 14 and spring 17. As the 100 slide plate 13 approaches the limit of its rearward movement, the slack in the chain 34 is taken up and the slide bar sections 27 and 30, together with the cylinder 35, plunger 37 and cylindrical member 56 are 110 moved downwardly against the tension of the spring 33, the cylindrical member 56 pressing against the butt or rear end of the shell and causing the primer to be removed by the pin 55. Subsequent to the release of 115 the foot pedal 16 the cylinder 35 and parts associated therewith are automatically returned to initial position under the influence of the spring 33 and the slide bar 13 and post 54 are moved forwardly to their initial position under the influence of the spring 26.

The next step is the insertion or setting of the new primer which is accomplished by means of the attachments shown in detail in Figs. 5 and 6 which are applied to 125 the parts of the loading machine as hereinbefore described. In this operation the shell to receive the new primer is positioned in an inverted position upon the post 71 and the primer (not shown) is placed in the bore 130

65 of the upper sleeve 64 and is stopped by the stop plate 66. As the pedal 16 is depressed and the slide bar 13 is moved rearwardly, the shell 70 is moved into engagement with the shell engaging member 68 thus moving the latter rearwardly together with the stop plate 66, the aperture 67 in which alines with the bores 65 of the sleeves 64 and permits the new primer to fall into position in the aperture in the butt or rear end of the shell 70. Upon further depression of the foot pedal 16 the slack in the chain 34 is taken up and the slide bar sections 27 and 30, cylinder 41 and plug 73 are moved downwardly, the plug 74 projecting through the bores 65 of the sleeves 64 and forcibly inserting the new primer in position in the shell. When the foot pedal 16 is released the parts of the machine are returned to initial position under the influence of the springs 26 and 33 and the shell may be removed from the post 71 and a new one to receive a new primer is substituted therefor.

The next step in the operation of the machine is the reloading of the shell and this is accomplished by the assistance of the shell holder 48 and rammer 40 shown in detail in Fig. 1.

In the operation of reloading the shell, the screw 43 is adjusted so as to permit the plunger 37 and rammer 40 to be yieldably retained in downwardly extended position by the tension of the spring 41. The empty shell is placed in the base member 47 and is secured in position by the holder 51 which latter is retained in adjusted position with relation to the base member 47 by the pin 50 which is engaged in the bayonet slot 49. The charge of powder and the proper wads are placed in the ring 52 and the foot pedal 16 is depressed thus moving the slide bar 13 rearwardly and subsequently depressing the rammer 40 which enters the ring 52 and compresses the powder in the shell and inserts the wads into position in the shell.

What is claimed is:—

1. A loading machine comprising a bed plate, a slide bar supported on said bed plate, a foot pedal, yieldable means connecting said foot pedal with said slide bar, a shell holder supported on said slide bar, a shell loading element associated with said shell holder, and means normally retaining the shell holder in position forwardly of the loading element.

2. A shell loader comprising a bed plate, a slide bar slidably supported upon said bed plate, a pivoted foot pedal, yieldable means connecting said foot pedal with said slide bar, a shell holder supported on said slide bar and movable therewith, a vertically movable shell loading element associated with said shell holder, and means connecting said loading element with said pivoted foot pedal.

3. A shell loader comprising a bed plate, a slide bar slidably supported upon said bed plate, a pivoted foot pedal, yieldable means connecting said foot pedal with said slide bar, a shell holder supported on said slide bar, a vertically movable rammer adapted to enter said holder, and means connecting said rammer with said foot pedal whereby the rammer is actuated subsequent to the rear stroke of the slide bar and shell holder.

4. A shell loader comprising a bed plate, a horizontally movable shell holder supported upon said plate, a vertically movable rammer adapted to enter the holder, a pedal, and independent connections between the pedal and holder, and the pedal and the rammer.

5. A shell loader comprising a bed plate, a shell holder movable horizontally over said bed plate, adjustable means for limiting the rearward movement of said shell holder, a vertically movable rammer associated with said shell holder, and means normally retaining said shell holder in forwardly extended position with relation to said rammer.

6. A shell loader including a bed plate, a horizontally movable shell holder supported on said bed plate, a standard, a vertically movable slide bar supported on said standard, a vertically movable rammer, means yieldably connecting said rammer with said vertically movable bar, means normally retaining said rammer in elevated position, means normally retaining said shell holder in forwardly extended position with relation to said rammer, a pivoted foot pedal, means connecting said foot pedal with said shell holder for moving the latter rearwardly into vertical line with said rammer, and means independent of the last-mentioned connecting means connecting said foot pedal with said rammer for depressing the latter subsequent to an actuation of the shell holder.

7. A shell loader comprising a bed plate, a horizontally movable shell holder supported on said bed plate, an upright or standard carried by said bed plate, a vertically movable slide bar supported in said upright, a cylinder carried by said slide bar, a rammer extending into said cylinder and adapted to project into said shell holder, means normally retaining said rammer in downwardly extended position, and spring means in said cylinder for absorbing the recoil movement of said rammer under the influence of the last mentioned means.

8. A shell loader comprising a bed plate, a shell holder supported on said bed plate, a standard carried by said bed plate, a vertically movable slide bar supported in said standard, a rammer adapted to enter the upper end of said shell holder, means yieldably connecting said rammer with said vertically movable slide bar, and adjustable

means for rigidly connecting said rammer with said slide bar.

9. In a shell loader, a bed plate, an upright supported upon the bed plate, a vertically movable slide bar supported in said upright, a cylinder carried by said slide bar, a plunger movable in said cylinder, a shell loading element carried by the plunger, yieldable means normally retaining the plunger in downwardly extended position, and means to lock the plunger against movement in the cylinder.

10. In a shell loader, a bed plate, an upright carried by the bed plate, a vertically

movable slide bar supported in said upright, a cylinder carried by said slide bar, a plunger movable vertically in said cylinder, a shell loading element carried by the plunger, and yieldable means resisting the upward or downward movement of the plunger in the cylinder.

In testimony whereof I affix my signature in presence of two witnesses.

EMORY C. ATHERTON.
